UNITED STATES PATENT OFFICE

DAVID S. KENNEDY, OF BROOKLYN, NEW YORK, ASSIGNEE TO MERGENTHALER LINOTYPE COMPANY, A CORPORATION OF NEW YORK.

TYPOGRAPHICAL MACHINE.

1,074,956.

Specification of Letters Patent. Patented Oct. 7, 1913.

Application filed January 22, 1913. Serial No. 743,475.

To all whom it may concern:

Be it known that I, DAVID S. KENNEDY, a citizen of the United States, residing at Brooklyn, in the county of Kings and State of New York, have invented certain new and useful Improvements in Typographical Machines, of which the following is a specification, reference being had therein to the accompanying drawing.

- 10 My invention relates to typographical machines, such as linotype machines of the general organization represented in Letters Patent of the United States, No. 436,532, to O. Mergenthaler, wherein circulating matrices 15 are released from a magazine in the order in which their characters are to appear in print and then assembled in line, the composed line transferred to the face of a mold, the mold filled with molten metal to form a slug 20 or linotype against the matrices which produce the type characters thereon, and the matrices thereafter returned through a distributing mechanism to the magazine from which they started. More particularly, it 25 relates to this style of machine when provided with a plurality of fonts or sets of matrices, any selected one of which may be brought into action when desired, and a principal object of the invention is the ability to secure the delivery of matrices in one 30 quantity from one font, or in another quantity from another font, at will. To this end, I have specifically illustrated my invention as adapted to two magazines each equipped 35 with escapements, and have arranged the actuating devices, so that pluralities of escapements may be actuated conjointly thereby in one of the magazines, or single escapements individually in the other magazine. Of 40 course, the same principles may be applied to other forms of typographical machines, such as type setters, type casters, and the like, which handle type or dies instead of matrices.
- 45 In my preferred form, I have illustrated my invention in connection with means for releasing the matrices, of the kind illustrated and described in the application for Letters Patent of William H. Rogers, Serial 50 No. 742,797, filed January 18, 1913, wherein a plurality of escapements may be actuated by the operation of a single key or the like. In the present instance, I apply these means to a machine having two magazines, and 55 wherein the escapements of corresponding

channels are actuated from the same keyboard element. The respective series of escapements are also provided with means whereby those of the non-operative magazine may be locked against movement. In this way, and by a simple manipulation of the parts, I am enabled to employ the same key to deliver matrices individually from a single channel in one magazine, or matrices conjointly from a plurality of channels in the other magazines, as may be desired.

In the accompanying drawings, I have shown my invention in preferred form and by way of example, and as applied to the form of mechanism already referred to, but it will be understood that many variations and alterations may be made therein, and in its mode of application, which will still be comprised within its spirit.

Generally speaking, I desire it to be understood that I do not limit myself to any specific form or embodiment, except in so far as such limitations are specified in the claims.

Referring to the drawings: Figure 1 is a 60 detached perspective view, partly in section and broken away, of the magazines and escapement-actuating mechanism, having my invention applied thereto; Fig. 2 is a plain view of a portion of the keyboard; Fig. 3 is a front view, showing a specific form of shifting means; Fig. 4 is a similar view, with the parts in different position; and Fig. 5 is an edge view of a pair of coöperating matrices.

The compound matrices X, as shown in Fig. 5, carry characters of unusual breadth, which therefore have to be divided between two or more matrices, which matrices may be successively and immediately delivered by the operation of a single key. It will be understood that my improvements are applicable not only to compound matrices of the style referred to, but also for many other purposes, such as for running quads, leaders, 100 or other matrices used for filling out extended spaces, etc. The matrices X are stored in the magazine A, their release therefrom being controlled by the escapements B, which are actuated by the reeds C, 105 cam yokes D, cams E, rolls F, triggers G, slides H, and key levers J, in the manner well understood in the art. As in the said Rogers application, the matrices X may be simultaneously or successively released from 110

a plurality of channels, this release being secured by the conjoint actuation of their respective escapements. In order to secure the connected actuation of the parts, the 5 slides H are provided with pivoted arms or members K, which may be swung laterally to engage studs L on adjacent or other slides H'; and to effect this movement of the arms or members K, I employ the movable element 10 M formed with recesses or notches N to engage pins O on the arms or members K. When the arms K are in the position indicated in Fig. 3, the operation of the key J acts to release successively a pair of matrices X from the magazine A. So far the 15 parts and their action are or may be substantially similar to those in the said Rogers application.

In the present case, I have illustrated the 20 second magazine A' as containing the matrices X', which are preferably of the ordinary style, and unlike the compound matrices stored in the magazine A. The magazine A' is provided with a series of escapements B' to control the release of the matrices X' therefrom, these escapements being actuated by the connected levers C', which are mounted in position to be moved by pieces C', projecting from the same reeds C 25 30 which actuate the escapements B of the magazine A. In other words, the operation of a single key J, would effect the simultaneous actuation of an escapement B of the magazine A, and of an escapement B' of the magazine A', were it not for the further devices now to be described.

Located in proximity to the escapements B of the magazine A is a locking device in the form of a rock shaft R, which in one 40 position holds the escapements B against actuation, and in another position leaves them free to act. The magazine A' is provided with a similar rock shaft R', arranged to lock the escapements B' thereof or 45 leave them free to act, as desired. The specific form and mode of action of these rock shafts R and R' constitute no part of my present invention. Similar parts are disclosed in Letters Patent of the United States 50 to George A. Bates, No. 719,422, wherein the two shafts are provided with connections and operating means, so that when one is turned to operative position, the other is moved to inoperative position, that is to say, 55 so that when the escapements of one magazine are locked, those of the other magazine are unlocked.

The operation of my improved devices 60 will now be readily understood. If it be desired to deliver the compound matrices X from the magazine A, the element M is moved to the position shown in Figs. 1 and 3, thereby shifting the arms K to connect the slides H and H'; and the rock shafts R 65 and R' are turned to unlock the escapements

B, and to lock the escapements B'. The operation of the key J now effects the conjoint and successive delivery of a pair of the compound matrices X, in the manner already described. If, however, it be desired to deliver the ordinary matrices X' from the magazine A', the element M is moved to the position indicated in Fig. 4, thereby breaking the connection between the slides H and H'; and the rock shafts R and R' 70 are turned to lock the escapements B and to unlock the escapements B'. The operation of the same key J now effects the individual delivery of a matrix X' from the magazine A' in the usual way. 75

I have illustrated the adjusting element M as distinct from and independent of the means for operating the rock shafts R and R', but obviously this element may be connected to the said means, so that a single 80 adjustment affects both the unlocking and locking of the escapements, and the corresponding connection and disconnection of the actuating slides.

As previously stated, I have shown my 85 invention only in preferred form and by way of example, and as applied to a particular style of machine, but obviously many variations and alterations may be made therein, and in its mode of application, 90 without departure from its scope. Thus, the same principles may be adapted to many different uses, and are by no means confined to the specific numbers of magazines or of 95 escapements described, nor to the specific forms of matrices set forth. Moreover, the precise form of the escapement-actuating devices, and of their connecting means, and of the mechanism for locking the matrices in 100 their respective magazines, are in themselves 105 unimportant. Modifications in these and many other respects will readily suggest themselves to those skilled in the art.

Having thus described my invention, its 110 construction, and mode of operation, what I claim and desire to secure by Letters Patent of the United States, is as follows:

1. In a typographical machine, the combination of a plurality of magazines for the type or matrices, and means whereby at a 115 single operation type or matrices may be delivered in one quantity from one of the magazines or in another quantity from another of the magazines, at will.

2. In a typographical machine, the combination of two magazines for the type or matrices, and means whereby type or matrices may be delivered either conjointly from one of the magazines or singly from the other, at will. 120

3. In a typographical machine, the combination of a plurality of magazines each provided with escapements, common actuating devices therefor, and means whereby the said devices may be adapted to actuate either 125 130

one number of escapements in one magazine or a different number of escapements in another magazine, at will.

4. In a typographical machine, the combination of two magazines each provided with escapements, common actuating devices therefor, and means whereby the said devices may be adapted to actuate either pluralities of escapements conjointly in one of the 10 magazines or single escapements individually in the other magazine, at will.

5. In a typographical machine, the combination of a plurality of magazines for the type or matrices, each provided with escapements and locking means to hold said escapements out of action, actuating devices for said escapements, and means to connect said actuating devices together when the escapements of a selected magazine are in 15 action; whereby the type or matrices may be delivered in one quantity from one of the magazines or in another quantity from 20 another of the magazines, at will.

6. In a typographical machine, the combination of two magazines for the type or matrices, each provided with escapements and locking means to hold said escapements out of action, actuating devices for said 25

escapements, and means to connect said actuating devices together when the escapements of a selected magazine are in action; whereby the type or matrices may be delivered either conjointly from one of the magazines or singly from the other, at will.

7. In a typographical machine, the combination of a plurality of magazines for the type or matrices, devices for releasing type or matrices therefrom, and controlling means whereby at a single operation the type or matrices may be delivered in one quantity 35 from one of the magazines or in another quantity from another of the magazines, at will.

8. In a typographical machine, the combination of two magazines for the type or matrices, devices for releasing type or matrices therefrom, and controlling means whereby the type or matrices may be delivered either conjointly from one of the magazines or 40 singly from the other, at will.

In testimony whereof I affix my signature in presence of two witnesses.

DAVID S. KENNEDY.
